P. K. SAPONOFF,
COVERING FOR FLOORS, STAIRS, AND THE LIKE,
APPLICATION FILED JULY 20, 1917.

1,292,889.

Patented Jan. 28, 1919.

Inventor
Peter K. Saponoff
By his Attorney

Willis Fowler.

UNITED STATES PATENT OFFICE.

PETER K. SAPONOFF, OF BROOKLYN, NEW YORK.

COVERING FOR FLOORS, STAIRS, AND THE LIKE.

1,292,889.

Specification of Letters Patent. Patented Jan. 28, 1919.

Application filed July 20, 1917. Serial No. 181,825.

To all whom it may concern:

Be it known that I, PETER K. SAPONOFF, a citizen of the United States, residing in Brooklyn, county of Kings, and State of New York, have invented certain new and useful Improvements in Coverings for Floors, Stairs, and the like, of which the following is a specification.

My invention relates to coverings or cushions for floors, stairs or like places and to certain adjuncts of the same and the principal objects of the improvements are to provide an article of this class that is neat, durable and attractive in appearance and which may be made dust and liquid proof so that it may be kept sanitary. My improved article is easily put in place and secured in position and at the same time may be readily detached for reversing it end for end or for the purpose of cleaning or repairing it. To these ends my invention consists in the various novel and peculiar combinations and arrangements of the several different parts of the article, all as herein-after fully set forth and then pointed out in the claims.

I have illustrated types of my invention in the accompanying drawings, wherein;

Figure 1 is a perspective view of part of a stairway, the treads and risers of which are provided with my improvements.

Fig. 2, is an enlarged cross-sectional view of one of the steps with my improved cushion and riser protector placed thereon.

Fig. 3, is an enlarged cross-sectional view of a modified form of the cushion and securing rim or piece.

Referring to the drawings in which like numbers of reference designate like parts throughout, 1, is the tread of the step having the overhang or nosing 2, and 3 is the riser. My improved cushion consists in an outer cover 5, made of a suitable fabric, such as ordinary carpet, which is cut to the size of the cushion and in the desired shape. A piece of material, such as paper board, is cut the same size as the cover in the form of a sheet 7, and then suitable padding material 9, is inserted so as to fill the space between the cover and sheet. A backing piece 12, is cut the same size and shape as the other two pieces and of a suitable material,

such as paper board, and its edges are secured to the edges of the other two pieces, so that the several parts are securely and permanently held together and the contained padding is prevented from working out through the joints at the edges. This method of securing these parts together also serves to keep the dust from entering through the edge joints. Over the sewed edges of the cushion I place the binding piece or frame 14, which is made from suitable sheet-metal formed U-shaped in cross-section and formed in one piece bent into a closed figure with the two secured together so as to form a flush joint upon the exterior of the frame to prevent the same from catching in foreign materials. The overlapping ends are formed with perforations 17, passing through both limbs of the frame and registering with each other when the parts are put together and receiving the attaching screw 18, which is screwed into the wooden tread, as shown in Fig. 1. This joint is formed on one of the short sides of the frame and within a short distance of the corner and there are two sets of such holes upon each side for securing the cushion by its side edges, as indicated at 18 and 19, so that four attaching screws may be used and this number will be sufficient, though more may be used, some of them being applied along the front and rear edges, as indicated at 20 and 21, Fig. 2, a screw 23, in each case passing through the two sides of the frame into the tread. As a rule, however, where attaching devices are applied to the front and rear sides of the cushion frame on a step, I use nails instead of screws as the wearing of the screw-head makes it difficult to remove with a screw-driver.

In Fig. 3, I show the floor or place to be covered, as upholstered, by means of the filling or padding 9^a, which is spread directly upon the floor where it is in good condition or is placed upon the back sheet of material 12^a, a sheet of flexible oil-cloth 31, being drawn snugly over the padding with the cloth or rough side upper-most so as to lie in contact with the under surface of the cover or carpet 5^a, placed thereover, both the oil-cloth and carpet being securely held

at each of their edges by the strip 14, which is held tightly in position by means of nails 32, driven through the strip and the materials. This construction is used for floor 5 cushions for rooms or other places, and in place of rugs, and the oil-cloth makes it both dust and liquid proof. The rough surface of the oil-cloth being in contact with the under surface of the overlying carpet or 10 fabric, holds the same from slipping and thereby avoids friction or rubbing of the two materials on each other, thus prolonging the life of the carpet. I also use this upholstery of padding and oil-cloth with 15 ordinary loose rugs which may be placed over the same and they are held in place by the roughness of the oil-cloth and saved from hard wear by the padding. These floor cushions may be made of any size or 20 shape and may be used on stair landings and in hall-ways.

Referring to the use of the stair cushions they are so made that they may be reversed by placing the front edge to the rear when 25 the front of the cushion begins to show signs of wear. For this purpose it will be noted that the screw-holes 17 and 19, in the side edges of the frame, are placed the same distance from the corners of the frame so 30 that when the cushions are reversed the same holes in the stair-tread may be used.

The riser protector 33, is secured directly to the face of the riser 3, and comprises an outer cover 34, of suitable fabric which as 35 a rule matches the cover of the cushion on the tread, a backing-piece 35, of the same length as the cover but narrower than the same and an intermediate sheet of material 36, of the same dimensions as the backing 40 and which like the backing may be made of suitable fibrous material such as paper-board. The cover is wider than the other two parts so as to provide at the lower end a free flap or extension 37 which is adapted 45 to lie on the sub-jacent tread 1, and extend well under the rear end of the cushion or pad 4, on the tread. When the protector is in place, the pad is then put down with its rear edge bearing firmly against the 50 protector to clamp it against the riser and hold the protector snug and the flap is held securely under the pad, making a neat and snugly fitting arrangement for the tread and riser. The protector may be omitted 55 and the pad used alone on the tread as preferred.

The two side edges and the upper edge of the protector are provided with a stiff metal frame or strip 39, which is formed U-shaped 60 in cross-section and is constructed like the pad frame 14, except there are three sides instead of four. This frame is clamped to the edges of the material forming the protector and when in place its two free ends

may rest upon the tread below and it is secured to the riser by means of screws 40, passing through the frame into the riser and I find that one screw upon each side is sufficient as the pad below acts as a clamp for the protector against the riser. 65

The height of the riser may be regulated to suit the taste and the particular conditions under which it is used. I show it about two-thirds the height of the riser but it may be made lower so long as it protects 70 the riser from being marked or marred by the shoes of the users of the stairs.

Either the protector or the stair pad or both may be made of the ordinary rubber used for floor coverings and with this material the pad and protector, one or both may be applied to the running-boards of motor-cars. The floor of the interior of the motor-car may also be provided with one of my cushions made of this rubber material 80 and in each case the neatness of my device will add to the trim appearance of the car and will be found sanitary and easy to keep clean. 85

It will be noted that my improvements 90 may be used for any size or shape of floor covering or cushion and that they are shaped to fit the contour of the place where the article is used, as indicated on the lower tread of the steps shown in Fig. 1, and I 95 prefer to use a margin of floor around the cushion or covering.

In cases where the oil-cloth is used between the cover and the padding, the cloth serves to keep the dust and water from 100 reaching the same and keeps the article sanitary and it will last a long time.

I wish to be understood as not limiting my invention to the particular constructions herewith shown, as it is evident that 105 various modifications may be made in the different parts thereof, without however departing from the spirit of the invention.

Having thus described my invention, what I claim and desire to secure by Letters Patent is:—

1. The combination of a stair covering or cushion adapted to be secured to the tread of the step, and a separate protector section adapted to be secured to the riser above said 115 tread and comprising a cover of suitable material and a stiff binding-piece or frame extending around three edges of said cover leaving the lower edge thereof flexible and adapted to lie under the rear edge of said 120 covering on the tread, substantially as described.

2. A dust proof floor covering or cushion, comprising an outer cover of fabric, a sub-jacent sheet of oil-cloth with its cloth or 125 rough side uppermost in contact with the underside of said cover to prevent the latter from sliding and thereby stretching, and

suitable filling beneath said oil-cloth, and means for securing said parts in place, substantially as described.

3. The combination of a stair covering or cushion adapted to be secured to the tread of the step, and a separate protector section adapted to be secured to the riser above said tread and comprising a cover of suitable material and a stiff binding-piece or frame 10 extending around three edges of said cover

with the ends of the frame terminating at the tread, substantially as described.

In testimony whereof, I have hereunto set my hand in the presence of the two subscribing witnesses.

PETER K. SAPONOFF.
